[57] CLAIM

The ornamental design for a combined fishing float carrier and rack for attachment to boats, substantially as shown and described.

DESCRIPTION

FIG. 1 is a perspective view of a combined fishing float carrier and rack for attachment to boats with the top in closed position, showing my new design;

FIG. 2 is a side elevational view thereof with the top pivoted to an open position and wherein the opposite side is a mirror image thereof;

FIG. 3 is a rear elevational view thereof with the top in closed position;

FIG. 4 is a top plan view thereof; and

FIG. 5 is a bottom plan view thereof.

FIG. 1

FIG. 2

FIG. 3

FIG. 4

FIG. 5
